AMMUNITION FEEDER

Ernest W. Stacey and Frank W. Reinhold, Beverly,
Mass., assignors to United Shoe Machinery Cor-
poration, Flemington, N. J., a corporation of
New Jersey

Application December 26, 1945, Serial No. 637,236

10 Claims. (Cl. 89—33)

1

This invention relates to ordnance and is illustrated as embodied in a machine for automatically feeding ammunition to 37 mm. guns installed in airplanes.

In the use of automatic guns in airplanes, it is desirable in firing short bursts at enemy targets to feed ammunition to the gun as fast as the gun can take said ammunition. Machines for feeding ammunition to guns mounted in airplanes should not only be fast and reliable in their operation but should also be light and compact.

With the above considerations in view, it is an object of the present invention to provide a satisfactory machine for effectively delivering clips of cartridges to 37 mm. guns mounted in airplanes, for example. In accordance with a feature of the present invention, there is provided in a machine for feeding ammunition to automatic guns of the above-mentioned type a magazine or housing for receiving cartridges assembled in groups in separate clips, mechanism for successively moving the clips of cartridges to a transfer station adjacent to a feed box of a gun, and means operative in timed relation with said mechanism for delivering in contacting succession the loaded clips to said feed box.

The clips of cartridges are loaded in stacked or tiered relation upon platforms arranged one above the other in said magazines which serves as a housing for the platforms and the clips of cartridges and is movable in azimuth and elevation together with the gun to be supplied with ammunition. Each platform comprises a plate and a spaced oppositely arranged channelled bar which are constructed and arranged to be engaged by the projectile portions and the rims of the cases of cartridges, respectively, assembled in a clip. The ammunition supporting plates and bars are secured at their lateral ends to links of oppositely arranged pairs of continuous chains which are geared together for movement in timed relation. Operatively connected to headers secured to the oppositely arranged pairs of chains, respectively, are heavy power springs which are progressively tensioned as the clips of cartridges placed successively upon the platforms in a loading or transfer station on the top of the housing are lowered into said housing, said springs serving as a source of power for moving, during firing of the gun, the tiers of cartridges successively back to said transfer station from which they are moved by a crossfeed assembly into the feed box of the gun.

The clips of cartridges placed upon the platforms moved successively to the loading or trans-

2

fer station are lowered into the housing in tiered relation by turning a manually operated crank against the action of said heavy springs. When twenty clips of cartridges have been stacked into the housing, said housing is full, and after swinging a clip guide, forming in effect part of the feed mechanism of the gun, back into an operative position adjacent to said transfer station, a clip of cartridges is manually fed into said guide into operative relation with a pawl carried by a feed slide of the gun, charging mechanism of the gun then being actuated to chamber the leading cartridge of said clip. The crossfeed assembly and an escapement arm of the machine are then swung into operative positions over the housing, a bar of the escapement arm riding upon an outer portion of the clip the inner portion of which is in the clip guide. As the next to last cartridge of said clip partly fed into the feed box is stripped from said clip, the bar of the escapement arm drops down onto the top clip of cartridges in the housing, causing a pawl in engagement with one tooth of a two-toothed ratchet, operatively connected to the two pairs of platform supporting chains, to be moved away from said one tooth of the ratchet to permit the ammunition supporting platforms in the housing to be elevated in the housing by said chains. As the escapement arm is raised by upward movement of the top clip of cartridges in the housing, the pawl is moved into such a position that it is engaged by the other tooth of the ratchet when said top clip of cartridges has been raised above the housing to the transfer station, with the result that the chains, and accordingly upward movement of the platforms, are stopped as said top clip of cartridges has been moved to said transfer station.

The crossfeed assembly for moving the clips of cartridges at the transfer station into the feed box of the gun comprises a spring-actuated spoked driver energized, in accordance with a feature of the present invention, by means movable in response to movement of the top clip of cartridges in the housing to the transfer station. When said top clip of cartridges arrives at the transfer station, the driver is immediately actuated to insure that the leading end of the clip at the transfer station shall be forced against the rear end of the clip which is in the feed box and at that time still has one cartridge to be stripped from it. Once the machine is adjusted for operation, twenty clips of cartridges in the housing are delivered automatically to the gun, said clips being moved successively from the housing or

magazine to the transfer station and upon arrival at said station being immediately transferred to the feed box of the gun.

The various features of the invention will be understood and appreciated from the following detailed description read in connection with the accompanying drawings, in which

Fig. 1 is a perspective view, partly broken away, showing an illustrative ammunition feeding machine and an associated 37 mm. gun assembled in an airplane turret;

Fig. 2 is a perspective view of the upper end of the machine and a portion of the gun as viewed from the outer side of the machine;

Fig. 3 shows in perspective the upper end of the machine and a portion of the gun as viewed from the rear, a clip guide, a crossfeed assembly and an escapement arm of the machine being shown in their inoperative positions ready to stack ammunition into a housing or magazine of the machine;

Fig. 4 is a diagrammatic view showing in detail mechanism by means of which clips of cartridges are fed successively to a transfer station preparatory to moving them into a feed box of the gun;

Figs. 5 and 6 are perspective views of the upper and under sides of said crossfeed assembly;

Figs. 7 and 8 are views showing in perspective cartridges assembled in two different types of clips which may be effectively used in the machine; and

Fig. 9 is a section on line IX—IX of Fig. 2 illustrating in detail mechanism for guiding clips of cartridges into a feed box of the gun.

The illustrative ammunition feeding machine, which is commonly referred to as an ammunition feed, is illustrated with reference to delivering ammunition in the form of clips of cartridges 20 (Figs. 3 and 4) to a feed box 21 (Figs. 1, 2 and 3) of a 37 mm. gun 22, the machine being movable in azimuth and elevation together with the gun, a breech casing or receiver 26 of which is mounted upon a trunnion block 24 (Fig. 1).

Each of the clips 28 (Figs. 3, 4 and 7), in which the cartridges 30 are assembled, consists of five units hinged together, each unit comprising a guide plate 32 provided with an opening 34 for receiving a pawl 33 (Fig. 9) of a feed slide 35 (Figs. 3 and 9) of the gun 22, and notches 36 (Figs. 3, 4, 7 and 9) for receiving holding and stop pawls (not shown) of feed mechanism of the gun. Secured to the guide plate 32 of each of the clip units is a yoke 40 (Figs. 7 and 9) depending legs of which are connected by pivot pins 42 to associated legs of yokes of an adjacent unit. Also secured to the plates 32 and arranged between the legs of the yokes 40 are leaf springs 44 between cooperating pairs of which the cartridges 30 are forced.

A rigid clip 46 (Fig. 8), which may be used instead of the clip 28, comprises a single guide plate 48, having formed in it a plurality of feed pawl receiving openings 50 and holding and stop pawl receiving notches 52. Secured to the plate 48 is an elongated yoke 56 provided with cartridge receiving recesses 58 and having secured to it pairs of leaf springs 60 between which the cartridges 30 are forced and which serve to retain the cartridges in their proper positions in the clip.

The clips of cartridges 20 are vertically arranged in stacked or tiered relation in a housing or magazine 62 (Figs. 1, 2 and 3) which has a capacity of twenty clips of cartridges. The clips of cartridges 20 are initially placed on top of

the housing 62, which is commonly referred to as a "stack housing," by a gunner, with rims 64 (Figs. 3, 4 and 8) of the cartridges 30 resting in channels 66 of bars 68 opposite ends of which are secured to one pair of endless chains 70 (Figs. 3 and 4), the projectile portions of the cartridges 30 resting upon plates 72 (Figs. 2, 3, 4 and 8) secured at their outer ends to another pair of endless chains 74 (Figs. 3 and 4). Preparatory to loading the clips of cartridges 20 into the stack housing 62, a crossfeed assembly 76 (Figs. 2, 3, 5 and 6), an arm 78 operatively connected to an escapement pawl or detent 80, and a guide 82 (Figs. 2, 3 and 9) for controlling movement of the clips of cartridges into the feed box of the gun are moved from their operative positions, shown in Fig. 2, to their "swung back" inoperative positions, shown in Fig. 3.

In loading the machine, the pairs of chains 70, 74 which carry the channel bars 68 and the plates 72 are operated in timed relation by moving a worm 84 (Figs. 1, 2 and 3) of a loading crank 86 into meshing engagement with a worm gear 88 secured to a shaft 90 and rotating said shaft to cause corresponding bars and plates, which together may be said to constitute platforms, holders, or units upon which the clips of cartridges are placed, to be lowered into the stack housing 62 against the action of batteries of springs 92, 94 (Figs. 3 and 4) operatively connected, through mechanism hereinafter described, to the pairs of chains 70, 74, respectively. As will be explained later, the springs 92, 94, tensioned by winding the ammunition supporting platforms down into the stack housing 62, supply power to deliver the platforms successively to a transfer or loading station 96 (Fig. 4) located at the top of the stack housing just above the plane 97 and in substantial alignment with a cartridge receiving opening 98 (Fig. 2) of the feed box 21 of the gun 22. The springs 92, 94 also supply power for operating the crossfeed assembly 76 to cause the clips of cartridges 20 which have been moved to said transfer station 96 to be delivered to the feed box 21 of the gun 22.

After the housing or magazine 62 has been filled by stacking into it twenty clips of cartridges arranged in tiered relation, the clip guide 82 is swung down into its operative position, shown in Fig. 2, and a clip of cartridges is then fed manually into said clip guide to the feed box 21 of the gun 22, the first round of said clip being chambered, through mechanism such as disclosed in Browning Patent No. 1,525,065 and in an application for United States Letters Patent Serial No. 659,053, filed April 2, 1946 in the names of Ernest W. Stacey and Augustus D. Willhauck, by actuating an operating lever (not shown) of a lock frame (not shown) of the gun and thereafter operating a charging handle 100 (Figs. 1 and 3) secured to a feed box slide 102 (Fig. 3) of said gun. The crossfeed assembly 76 and the escapement pawl actuating arm 78 are then swung from their inoperative positions, shown in Fig. 3, to their operative positions, shown in Fig. 2.

As the fourth cartridge of the manually inserted clip is stripped from said clip, a bar 104 (Fig. 3), which forms part of the escapement 70 pawl actuating arm 78 and has heretofore rested on the plates 32 of the clip of cartridges entering the feed box 21, drops down on the plates 32 of the top clip of cartridges in the housing 62, that is, upon the underneath tier of cartridges, thereby releasing through mechanism which will be

hereinafter described, the two pairs of chains 70, 74 so that they may be actuated by the springs 92, 94 to cause the next lower tier of cartridges to be hoisted to the transfer station 96. As the clip of cartridges moves to the transfer station 96, it powers a torsion spring 106 (Figs. 2, 3, 5 and 6) forming part of the cross-feed assembly 76, said spring being released upon the arrival of said clip of cartridges at the transfer station, with the result that spokes 108 of a driver 110, which are secured to a shaft 112 (Figs. 3, 5 and 6) of said assembly and are arranged adjacent to the last or outermost cartridge in the clip, force said cartridges into the feed box 21 of the gun 22. The construction and arrangement of the crossfeed assembly 76 are such that the trailing end of the clip 28, or 46, during the last part of its movement through the feed box of the gun is engaged by the leading end of the following clip, thereby insuring that the separate clips of cartridges shall be fed continuously, as in a continuous belt feed, to the feed box 21. Once the delivery of cartridges to the feed box 21 is established, no further attention is required until all the rounds of ammunition in the stack housing 62 have been fired, the cartridges being delivered to the feed box as fast as the gun can chamber them.

The stack housing 62 comprises web side plates 114, 116 (Figs. 1, 2 and 3), a front plate 118, a spring retaining case 120, and a base 122 (Fig. 1) which are screwed or otherwise secured together. The base 122 is rigidly secured to a turret 124 formed partly by a girth ring 126 to which are secured trunnions 127. The trunnions 127 are journaled upon a rotatable azimuth ring 128 and are rotatable in azimuth together with the ring and together with the turret 124 upon said ring. The trunnion block 24 of the gun 22 is secured to a cradle 130 fixed to the turret 124. With the above construction, it will be clear that the loading machine and the gun move together as a unit in azimuth and elevation.

Supported upon four laterally extending studs 132 (Fig. 3) of the feed box 21 of the gun 22 is a plate 134 (Figs. 2 and 3) having extending from it flanges which are secured by screws 136 to the stack housing 62. The stack housing 62 is properly positioned with relation to the gun by the plate 134, the base 32 then being adjusted to the proper position and being rigidly secured by suitable means in said adjusted position to the turret 124 (Fig. 1). Fulcrumed upon a rod 138 mounted upon the plate 134 is the clip guide 82 which is provided at its underside with ways 140 (Figs. 3 and 9) for receiving the plates 32, 48 of the clips 28, 46, respectively, and may be swung from its operating position, shown in Figs. 2 and 9, to its "swung back" inoperative position, shown in Fig. 3, when the stack housing 62 is to be filled with clips of cartridges.

The ways 140 of the clip guide 82 are held in operative position in proper alignment with the pawl 33 of the feed slide 35 of the gun by a spring-pressed plunger 144 which latches beneath an abutment 146 (Figs. 3 and 9) to hold the guide in operative position and which is pulled out preparatory to swinging the guide back to its inoperative position. Before moving the clip guide 82 back to its inoperative position, it is necessary to pull the charging handle 100 of the gun 22 far enough rearward to cause the feed slide 35 of the gun to be retracted clear of the clip guide. Bolted to the plate 134 are a pair of channeled guide arms 148 (Fig. 2), 150 (Figs. 2 and 3)

ammunition supporting portions of which are in alignment with the bottom of the cartridge receiving opening 98 in the feed box 21 and are in approximate alignment with lower portions of the cartridges arranged at the transfer station 96.

5 Mounted upon sprockets 152 (Figs. 3 and 4), 154 (Fig. 4) secured to upper and lower stub shafts 156, 158, respectively, rotatably mounted in the stack housing 62 are the plate supporting chains 74, and mounted upon sprockets 160, 162 secured to a shaft 164 and stub shafts 166, respectively, rotatably mounted in the stack housing are the bar supporting chains 70. After the crossfeed assembly 76, the arm 78, and the clip guide 82 have been swung into their inoperative positions out of the way, as above explained, the clips of cartridges are placed successively upon associated bars 68 and plates 72 at the loading station 96, the rims 64 of the cartridges 30 assembled in the 10 clips engaging in the channels 66 of the bars 68 and the projectiles of the cartridges lying upon flat surfaces of the plates 72. It will be noted that the plates 72 are provided with notches 168 (Figs. 3, 4 and 8) which engage the cartridges of 15 the next lower clip stored in the housing 62 and insure against any lateral movement of the clips of cartridges in said housing.

Connected to the central portion of a header 170 (Fig. 4) opposite ends of which are secured 20 to the endless chains 70 is a chain 172 which passes around a pulley 174 rotatably supported upon a shaft 176 secured to the stack housing 62, over a pulley 178 rotatably supported by a frame 180, to which the lower ends of the springs 92 25 are fixed, and around another pulley 182 rotatably supported upon a shaft 183 mounted upon the stack housing, the end of the chain being fixed to the frame 180. Connected to the central portion of a header 184 secured at its opposite ends to the endless chains 74, respectively, 30 is a chain 186 which passes over pulleys 188 rotatably mounted in the housing 62, over a pulley 190 rotatably mounted in a frame 190 fixed to the lower ends of the springs 94, and connected, after 35 passing over a pulley 192 also rotatably mounted on the housing 62, to the lower end of the frame 190. The upper ends of the springs 92, 94 are 40 attached to headers 187, 189 (Fig. 3) which are secured to the top of the spring retaining casing 120. With the above arrangement, it will be 45 appreciated that the vertical movement of the bars 68 and the plates 72 is three times that of the frames 180, 190 which are secured to the lower 50 ends of the springs 92, 94, respectively.

55 The shaft 90 has secured to its outer and inner ends at the inside of the housing 62 gears 194, 196 (Figs. 3 and 4) which mesh with gears 198, 200, respectively, rotatably mounted upon a shaft 202 journaled in bearings supported by the opposite side plate 114, 116 of the housing. The gears 198, 200 are in driving relation with gears 203 (Fig. 4) secured to the stub shaft 184, rotation of the shafts and the sprockets 160 carried thereby causing rotation of the endless chains 70. Secured to the outer end of the shaft 90 outside the housing 62 is a sprocket 204 (Figs. 1, 2 and 4) which is operatively connected to a sprocket 206 secured to a shaft 208, rotatable in 60 bearings of the side plates 114, 116 of the housing, by a chain 209. The tension of the chain 209 may be varied by the use of an idler sprocket 210 (Fig. 2) which is rotatably mounted upon an arm 212 adjustably held in a desired position by a screw 214. Mounted inside the housing 62 and secured to the shaft 208 are gears 216 (Fig. 4)

which mesh with gears 218 respectively secured to the upper stub shafts 156 to which are secured the sprockets 152 for driving the plate carrying chains 74.

The crank 86 is mounted for rotation upon a rod 220 (Fig. 3) fixed to the housing 62, said crank being normally forced by a spring 222 into a position in which the worm 84 is out of engagement with the worm gear 88. When the crank 86 is pressed inward against the action of the spring 222 and is rotated, the worm 84 meshes with the gear 88 and is drawn against the housing, continued rotation of the crank causing rotation of the shaft 90. It will be apparent that the manual rotation of the shaft 90 upon turning the crank 86 causes, through the mechanism above described, the pairs of chains 70, 74 to move clips of cartridges placed in the transfer station upon the upper channeled bar 68 and the plate 72, as shown in Fig. 4, downward into the stack housing 62 against the action of the springs 92, 94. When a following channeled bar 68 and plate 72 have been swung over the sprockets 160, 152, respectively, to the transfer station and another clip of cartridges has been placed upon said bar and plate, the crank is again turned to lower the clip of cartridges down into the housing 62 against the action of the springs 92, 94, such action being repeated until twenty clips of cartridges have been loaded into stacked or tiered relation in the housing.

Secured to the shaft 90 is a two-toothed ratchet 224 (Figs. 1, 2 and 3) against which the escapement pawl 80 is constantly forced by a spring 226. The pawl 80 is pivotally mounted upon the shaft 202 and is held against lengthwise shifting movement upon the shaft. Also loosely mounted upon and held against lengthwise shifting movement on the shaft 202 is a yoke 230 (Figs. 2 and 3) carrying a rod 232 passing through bores in the rear end of the escapement arm 78, the arm having extending shoulders 231 (Fig. 2) which normally engage inwardly extending pins 233 secured to the yoke. As best shown in Fig. 2, a boss of the pawl 80 is provided with an arcuate notch 234 into which extends a shoulder of the yoke 230, the arrangement being such that when the yoke has been rotated counterclockwise, as viewed in Fig. 2, upon downward movement of the arm 78 by reason of the bar 104 being permitted to drop from the plate 32 of the clip of cartridges entering the feed box 21 of the gun down onto the plates of the top clip of cartridges in the housing 62, the yoke will cause the pawl to move counterclockwise away from one of two teeth 236 of the ratchet 224 with which said pawl then engages.

As the gunner turns the crank 86 to lower into the housing 62 the channeled bars 68 and the plates 72 constituting the platforms upon which the clips of cartridges have been placed, the ratchet 224 engaged by the pawl 80 will rotate counterclockwise, as viewed in Fig. 2. When the crank 86 has been turned clockwise the proper amount to move the next platform into a position to receive the following clip of cartridges, the pawl 80 falls behind one of the teeth 236 of the ratchet 224, thereby insuring against upward movement of the clips of cartridges in the housing 62 under the action of the spring 92, 94 in case the worm 84 should become disengaged from the worm gear 88. It will be noted, however, that when the worm 84 is in driving relation with the worm gear 88 it locks the gear against movement under the action of the springs 92, 94, the gunner

being able to release the crank 86 at any time without danger of the tiers of cartridges in the housing 62 being moved. Accordingly, the mechanism by which the clips of cartridges are loaded in the housing 62 may be described as self-locking.

When twenty clips of cartridges have been stacked in the housing 62, the uppermost clip of cartridges is positioned just below the plane indicated by reference numeral 97 (Fig. 4), said plane being just below the transfer station 96. As above explained, after swinging the clip guide 82 down into its operative position, the clip of cartridges is placed in the transfer station 96 and is inserted manually into the feed box 21 of the gun 22.

Before swinging the crossfeed assembly 16 back into its operative position, shown in Fig. 2, the escapement arm 78 is swung inward from its inoperative position, shown in Fig. 3, to its operative position, shown in Fig. 2, the bar 104 at the forward end of the arm being pressed against the guide plates 32 of the clip of cartridges already partly fed manually into the feed box 21, by a leaf spring 242 (Figs. 2 and 3) carried by a block 244 secured by screws 246 to a supporting frame 248 of the crossfeed assembly. As the clip of cartridges advances into the feed box 21 to strip the next to the last cartridge from the clip, the bar 104 drops behind the clip of cartridges onto the plates 32 of the top clip of cartridges arranged in the housing just below the plane 97, with the result that the pawl 80, operating against the action of the spring 226 and under the action of the spring-actuated arm 78 and the yoke 230, is moved counter-clockwise, as viewed in Fig. 2, away from one of the teeth 236 of the ratchet 224, thereby enabling the shaft 90 to rotate under the action of the springs 92, 94 and accordingly the ammunition supporting platforms in the housing 62 to be elevated. As the top clip of cartridges previously in stacked relation in the housing 62 is elevated to the transfer station 96, it raises with it the escapement arm 78, together with the yoke 230, and permits the pawl 80 actuated by the spring 226 to rotate into such a position that it is engaged by the following tooth 236 of the ratchet 224, which is moved through mechanism above described in timed relation with the chains 70, 74, thereby stopping rotation of the ratchet 224 and accordingly movement of the tiered clips of cartridges, the construction and arrangement being such that said movement of the ratchet and the chains ceases when said top clip of cartridges has been moved to the transfer station 96 ready to be acted upon by the crossfeed assembly 16.

As above stated, the clip of cartridges in the transfer station 96 is slid into the feed box 21 of the gun 22 by the crossfeed assembly 16, which will now be described in detail and is energized in response to movement of the uppermost clip of cartridges in the stack housing 62 to the transfer station. The crossfeed assembly 16 is mounted in the frame 248 (Figs. 2, 3, 5 and 6) which has secured to it a pair of studs 250 (Figs. 2 and 3) rotatably mounted in bearings 252 of the stack housing 62. The frame 248 is locked in its horizontal position by a pair of latches 254 which are secured to a rod 256 (Figs. 2, 3 and 5) rotatably mounted in the frame and have hooked ends shaped and arranged to be swung under abutments 258 of the housing. The latches 254 are normally urged toward latching positions by a spring 260 one end of which is secured to the frame 248 and the other end of which is secured

to a collar 262 fixed to the rod 256. When the latches 254 are released the frame rises to an inoperative position, shown in Fig. 3, under the action of a spring 264 (Fig. 2) one end of which is fixed to the frame 248 and the other end of which is attached to a collar 266 fixed to the stack housing.

As previously stated, the shaft 112, which is mounted for rotation in the frame 248, has secured to its opposite ends the spokes 108 of the driver 110. When the crossfed assembly 76 is in its operative position, the spokes 108 are approximately engaged by the outermost cartridge of the clip in position ready to be transferred to the feed box 21 of the gun 22, as illustrated in Fig. 2. The driver is powered by the actuator spring 106 one end of which is attached to one of the spokes 108 and the other end of which is attached to a ratchet 268 (Figs. 3, 5 and 6) rotatable upon the shaft 112.

Secured by screws 270 (Figs. 2 and 5) to the frame 248 is a bracket 272 (Figs. 2, 3, 5 and 6) which carries a pin 274 upon which is pivoted a link 276 pivotally connected through a pin 278 to a drop arm 280. Rotatable upon a pin 282 (Figs. 3 and 6) carried by the lower end of the drop arm 280 are rolls 284 which are forced against the plates 32 of the clip of cartridges in the transfer station 96 by a spring 286 the upper end of which is fixed to the pin 278 and the lower end of which is fixed to the frame 248. As the next to the last cartridge in the clip in the feed box 21 of the gun 22 is stripped from the clip, the rolls 284 under the action of the spring 286 drop onto the plates of the next lower clip of cartridges, that is, the upper clip of cartridges in the stack housing. As said upper clip of cartridges is raised to the transfer station 96 by mechanism above described, the arm 280 is forced upward, causing a pawl 288 (Figs. 3, 5 and 6) mounted upon a stud 290 carried by the arm to rotate the ratchet 268 counterclockwise, as viewed in Figs. 5 and 6, against the action of the spring 286, thus additionally loading the actuating spring 106, the shaft 112 at this time being held against rotation by the engagement of a pawl 292, rotatably mounted upon a pin 294 (Figs. 3 and 6) secured to the frame, with one of the shoulders 296 (Figs. 5 and 6) of a ratchet 298 secured to the shaft. The arm 280 together with the pawl 288 carried thereby may be referred to as a charger.

The pawl 292 has rotatably mounted on it a roll 300 (Figs. 3 and 6) and is normally urged into its shaft locking position by a spring 302 (Fig. 5) the upper end of which is attached to a pin 304 fixed to the frame 248 and the lower end of which is fixed to the pawl. The ratchet 268 is constantly held against unwinding movement under the action of the actuator spring 106 by a pawl 306 (Figs. 5 and 6) hinged upon a pin 308 (Fig. 5) carried by the bracket 272 and constantly forced against the ratchet 268 by a spring-pressed plunger 310 (Figs. 5 and 6) slideable in the frame. The actuator spring 106 is initially energized by turning the driver in a clockwise direction, as viewed in Fig. 6, the pawls 306, 292 acting against shoulders of the ratchets 268, 298, respectively, to maintain the initial loading of the spring.

As the drop arm 280 is elevated by the upper clip of cartridges being moved to the transfer station 96 in the housing 62, the actuator spring 106 is energized by the action of the pawl 288 mounted on the stud 290 of the arm 280. When the clip of cartridges arrives at the transfer station 96, the roll 300 on the pawl 292 is engaged by the plates

32 of said clip, causing the pawl to be moved away from the shoulder 296 of the ratchet 298. Since the ratchet 268 is being held by the pawl 306, the shaft 110 will rotate under the action of the spring 106, causing the driver 110 to move the leading plate 32 of the clip into the ways 140 (Figs. 3 and 9) of the clip guide 82 and the cartridges assembled in the clip to slide over the arms 148 (Fig. 2), 150, the leading cartridge assembled in the clip being moved into the side opening 98 of the feed box 21 of the gun 22 and the feed pawl 33 (Fig. 9) of the feed slide 35 to engage the leading opening 34 in the clip ready to feed the clip automatically to the gun. Before the 15 clip of cartridges has moved a substantial distance, the roll 300 slides off the end of the clip, allowing the pawl 292 to be forced against the ratchet 298 secured to the shaft 112 before the following shoulder 296 of the ratchet moves into engagement with the pawl, the construction and arrangement being such that as said following shoulder engages the pawl 292 rotation of the shaft 112 ceases, the spokes 108 of the driver 110 being stopped in such positions that the cartridges of the next clip may be moved upward into their proper positions ready to be driven into the feed box.

Having described our invention, what we claim as new and desire to secure by Letters Patent of the United States is:

- 30 1. In a machine for feeding ammunition to automatic guns, means for receiving cartridges assembled in groups in separate clips, mechanism for feeding said clips of cartridges successively to a transfer station adjacent to a feed box of a gun, and means energized by and operated in timed relation with said mechanism for delivering said clips of cartridges to the feed box of the gun.
- 35 2. In a machine for feeding ammunition to automatic guns, platforms upon which cartridges assembled in groups in separate clips are positioned, power means operatively connected to said platforms, means for successively moving said platforms actuated by said power means into a predetermined position in alignment with a feed box of a gun, and means energized by said power means for successively feeding the clips of cartridges in said predetermined position into said feed box.
- 40 3. In a machine for feeding ammunition to automatic guns, platforms upon which cartridges assembled in groups in separate clips are positioned, power means operatively connected to said platforms, means operated by said power means for moving the platforms successively to a transfer station adjacent to a feed box of a gun, spring-operated means for moving the clips of cartridges successively from the transfer station into the feed box of the gun, and means operative in timed relation with the platforms for powering said spring-operated means and for releasing said means to cause the clip of cartridges in said station to be transferred into the feed box of the gun.
- 45 4. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 50 5. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 55 6. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 60 7. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 65 8. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 70 9. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism
- 75 10. In a machine for feeding ammunition to automatic guns, a magazine, a plurality of platforms constructed and arranged to support cartridges assembled in groups in separate clips in stacked relation in said magazine, spring-actuated means for successively moving the platforms and accordingly the clips of cartridges to a transfer station adjacent to a gun, means for successively moving the clips of cartridges at said station into a feed box of the gun, a detent operatively connected to the platforms, mechanism

responsive to movement of a clip of cartridges being moved into the feed box for releasing said detent to cause the platforms acted on by said spring-actuated means to move, thereby delivering a following clip of cartridges in said magazine to the transfer station, said mechanism also being responsive to movement of said clip of cartridges to the transfer station to cause said detent to stop movement of the platforms when said following clip of cartridges arrives at said transfer station.

5. In a machine for feeding ammunition to automatic guns, pairs of endless chains operatively connected together for movement in timed relation, platforms which are secured to said pairs of chains and are constructed and arranged to support cartridges assembled in groups in separate clips, spring-actuated members operatively connected to the chains for constantly urging the platforms toward a transfer station from which the clips of cartridges are moved to a feed box of a gun, a detent for stopping movement of the chains and accordingly movement of the platforms, and mechanism which is operatively connected to the detent and is responsive to movement of said clips of cartridges away from said transfer station, said mechanism being constructed and arranged to operate said detent to cause said platforms to be moved toward said transfer station by action of said spring-actuated members upon said chains, thereby causing a clip of cartridges upon a following platform to be moved to the transfer station, said mechanism also being responsive to movement of said clip of cartridges being moved to said transfer station and being constructed and arranged to move said detent to a position in which it arrests movement of the platform when the clip of cartridges on said following platform arrives at the transfer station.

6. In an ammunition feeder for automatic guns, two pairs of endless chains, plates secured to one pair of chains, channeled bars secured to the other pair of chains opposite the plates respectively of the first pair of chains, means for operating said pairs of chains in timed relation to cause clips of cartridges supported by the opposite pairs of plates and bars to be moved successively to a transfer station adjacent to a feed box of a gun, means for successively feeding the clips of cartridges from the transfer station to said feed box, and means operative in response to movement of the clips of cartridges from the transfer station to the feed box and movement of the clips of cartridges to said transfer station for causing starting and stopping of the chains and accordingly of the plates and bars.

7. In combination with an automatic gun which is movable in azimuth and elevation and has a feed box, an ammunition feeder comprising a housing movable in azimuth and elevation together with the gun, spaced pairs of endless chains therein which are operatively connected for movement in timed relation, oppositely arranged plates and channeled bars secured to opposite pairs of chains respectively and constructed and arranged to support cartridges assembled in groups in separate clips, spring-powered means which are secured to said pairs of chains and are constructed and arranged constantly to urge said plates and bars in the housing and the clips of cartridges supported thereby toward a transfer station arranged adjacent to a feed box of a gun, a crossfeed assembly for successively moving clips of cartridges at the transfer station into the feed box of the gun, and mechanism comprising a detent

10 operatively connected to said chains for limiting movement of the chains under the action of said spring-powered means when corresponding plates and bars are arranged at said transfer station, 5 said mechanism comprising a pawl which is responsive to movement of the clips of cartridges away from and toward said transfer station and cooperates with the detent to check movement of the detent upon arrival of a clip of cartridges at the transfer station.

8. In an ammunition feeder for automatic guns, a housing for receiving cartridges which are assembled in groups in separate clips in tiered relation, means for delivering said clips of cartridges successively from the housing to a transfer station located adjacent to a feed box of a gun, a crossfeed assembly for delivering clips of cartridges at said station successively to said feed box, said assembly comprising rotatable spokes positioned adjacent to an end cartridge of each of the clips of cartridges moved to the transfer station, a spring for actuating said spokes, means actuated by the clip of cartridges as it moves to its transfer position for loading the spring, and means actuated by the clip of cartridges when it arrives at the transfer station for releasing said spring to cause the spring to drive the rotatable spokes and accordingly to move the clip of cartridges into the feed box.

30 9. In an ammunition feeder for automatic guns, a crossfeed assembly for moving cartridges assembled in groups in separate clips from a transfer station, to which said clips of cartridges are moved successively, to a feed box of a gun, said assembly comprising a rotatable shaft, pairs of circumferentially arranged spokes secured to the shaft, a ratchet rotatably mounted upon the shaft, a coil spring surrounding the shaft and fixed at one end to one of the spokes and at the other end to the ratchet, a detent for enabling the ratchet to rotate a substantial distance in one direction only upon the shaft, a charger which operates against the ratchet and is movable under the action of a clip of cartridges being delivered to the transfer station to energize the spring, a lock for securing the shaft against movement under the action of the spring, and means for releasing said lock as the clip of cartridges arrives at the transfer station, thereby causing the spokes to force the clip of cartridges into the feed box of the gun.

10 10. In a machine for feeding ammunition to a gun, a rotatable driver constructed and arranged for positioning adjacent to an end cartridge of cartridges assembled in a group in a separate clip moved to a transfer station located adjacent to a feed box of a gun, a spring for rotating said driver to feed said clip of cartridges into the feed box, means for energizing said spring, mechanism for retaining said driver against rotation, means responsive to movement of the clip of cartridges to said station for rendering said mechanism inoperative to permit the spring to cause the driver to move said clip of cartridges into the feed box of the gun, and means responsive to movement of said clip of cartridges into the feed box for again rendering said mechanism operative to retain said driver against movement.
